LADDER RUNG

Charles W. Tunstead, Minneapolis, Minn.

Application September 6, 1956, Serial No. 42,858

Term of patent 3½ years

(Cl. D15—8)

FIG. 1.

FIG. 2.

FIG. 3.

FIG. 4.

FIG. 6.

FIG. 5.

Figure 1 is a perspective view of my new ladder rung.
Figure 2 is a top plan view of the design shown in Figure 1.

Figure 3 is a side plan view of my new design ladder rung.

Figure 4 is a bottom plan view of the design shown in Figure 1.

Figure 5 is an end plan view of my new design and ladder rung.

Figure 6 is a sectional view through the ladder rung on the line 6—6 of Figure 2.

I claim:

The ornamental design for a ladder rung, as shown.
